UNITED STATES PATENT OFFICE.

STEWART L. McCURDY, OF PITTSBURGH, PENNSYLVANIA.

GAME APPARATUS.

1,030,108.

Specification of Letters Patent. Patented June 18, 1912.

Application filed October 14, 1911. Serial No. 654,595.

To all whom it may concern:

Be it known that I, STEWART L. McCURDY, a citizen of the United States of America, residing at Pittsburgh, in the county of Allegheny and State of Pennsylvania, have invented certain new and useful Improvements in Game Apparatus, of which the following is a specification, reference being had therein to the accompanying drawing.

10 This invention relates to a game apparatus, and the primary object of my invention is to provide an apparatus designed along the lines of a baseball game, the apparatus possessing all the plays and fine 15 points of the ordinary baseball game, thereby affording considerable amusement to adults as well as juveniles, it being possible to construct the game apparatus upon a very large scale whereby it can be participated in 20 by adults representing "nines" or clubs, or made upon a very small scale simply to interest juveniles.

Another object of this invention is to provide a game apparatus by which a game of 25 baseball can be played, provision being made whereby the players will have practically the same chance of success as the players of league games.

A further object of this invention is to 30 provide a baseball game apparatus with simple and effective means for projecting a ball in various directions upon a field or board that is divided to indicate the various plays.

35 A still further object of this invention is to provide a baseball game apparatus that is simple in construction, durable, and highly efficient as an amusement device.

With the above and other objects in view, 40 the invention resides in the novel construction, combination and arrangement of parts to be hereinafter specifically described and then claimed.

Reference will now be had to the drawings, wherein like numerals denote corresponding parts throughout the several views, in which:—

Figure 1 is a plan of the game apparatus, Fig. 2 is a longitudinal sectional view of the 50 same, Fig. 3 is an enlarged longitudinal sectional view of a portion of the apparatus, Fig. 4 is an enlarged perspective view of a portion of the apparatus, illustrating a modified form of opening, Fig. 5 is a cross 55 sectional view of a portion of the apparatus, Fig. 6 is a side elevation of the same, Fig. 7 is a plan of a portion of a modified form of apparatus, Fig. 8 is a longitudinal sectional view of the same, Fig. 9 is a plan of a portion of the apparatus showing a modified 60 form of opening, and Fig. 10 is a perspective view of a portion of the apparatus showing the preferred form of opening.

A game apparatus in accordance with this invention comprises a rectangular frame having side walls 1, 2, 3 and 4 connected by a horizontal plate or "field" 5 located adjacent to the upper edges of said walls. The field 5, as it will be hereinafter termed, has the edges thereof cut away adjacent to the 65 walls 1 and 2 to provide slots 6 for the fielding or return of balls to the home plate, as will presently appear. The plate or field 5 is provided with an opening 7 at one end thereof.

Printed or otherwise marked upon the field 5 are the boundary lines 8 of a diamond, the home plate, first, second and third bases being represented by openings 9 and 10.

Journaled in the opening 10 is a vertical 70 shaft 11 having the lower end thereof mounted in a bearing 12, carried by an inclined return plate 13 arranged within the rectangular frame of the apparatus, said plate inclining from the walls 1 and 2 to 75 the walls 3 and 4, whereby a ball or spherical body passing through the openings 6 will be returned to an opening 14 at the juncture of the walls 3 and 4, this opening being in communication with a cup 15, 80 carried by said walls.

Mounted upon the shaft 11 is a balance wheel 16 and secured to the upper end of the shaft above the field 5 is a receptacle 17. This receptacle is circular in plan with the 85 top and bottom walls thereof convex, the top wall having a central opening 18 whereby a ball can be deposited in said receptacle. The receptacle has four radially disposed discharge spouts 19, two of said 90 spouts being in the same horizontal plane, while the other two of said spouts are so positioned as to project above and below the horizontal plane of the receptacle, whereby 95 when a ball is placed in the receptacle and said receptacle revolved, the ball will be hurled or discharged through one of the spouts by centrifugal force, the direction it takes being a matter of chance on account of the disposition of the discharge spouts. 100 This receptacle represents home plate and a "batter", and the said receptacle is adapt-

ed to be spun or revolved in a horizontal plane by striking or twirling said receptacle, whereby the ball within said receptacle will be projected over the field and in 5 all probability against the walls 1 to 4 inclusive.

The field 5 is provided with sets of vertical partitions 20, 21, 22, 23 and single partitions 24, all of these partitions being disposed upon lines radiating from the home plate. The partitions 24 represent prolongations of the lines connecting home plate and first and third bases, these partitions distinguishing between "fair" and "foul" 10 balls. The partitions 20 provide a passageway for balls that indicate "out on bases", the partitions 21 "passed balls" and "wild pitches", the partitions 22 "batter hit" and "runner hit" and the partitions 23 "stolen 15 bases". The space between the partitions 21 and 22 is designated upon the field "strikes", between the partitions 21 and 20 "balls", between the partitions 22 and 23 "balls", and the spaces between the partitions 24, 20 and 23 "foul". The field 5, at 20 the stations of the pitcher, first, second and third basemen, shortstop, fielders and such positions to which the right and left hand fielders may assume to catch foul balls, is 25 provided with sector-shaped openings 25.

In Figs. 4 and 9 of the drawings there are illustrated modified forms of openings. As shown in Fig. 4 there are two openings 28^a divided by a web 27, and the forward 30 edges of said openings are beveled. The web 27 represents errors, that is, when a ball passes over a web without entering one of the openings 28^a. In Fig. 9 of the drawings, the semi-circular opening 25^b has 35 the rear wall thereof provided with a tongue 27^a extending in proximity to the forward beveled edge of said opening. In either instance, when the ball passes through the openings, they are collected in the cup 15 through the medium of the inclined return plate 13. The field 5, adjacent to the wall 1, is provided with vertical partitions 29 arranged in parallelism. When a ball 20 passes between these partitions into the opening 6, a "home run" has been made. Arranged upon the bottom side of the field 25 are bearings 30 and pivotally mounted in these bearings by pins 31 are levers 32. The levers 32 extend to the openings 9 and 35 are bent up, as at 33 to enter said openings when the bases are supposed to be filled or one of said bases occupied by a player. The levers 32 extend through bayonet-shaped slots 34 provided therefor in the wall 4 of the 40 partition, the bayonet-shaped slots permitting of said levers being locked in an adjusted position.

In Figs. 7 and 8 there is illustrated a modification of the invention, wherein the 45 shaft 11 has a pinion 35 meshing with a

rack 36, carried by a rod 37 slidably mounted in bearings 38, carried by the under side of the plate 5. The rod 37 extends through an opening 39 provided therefor in one of the walls of the apparatus. By pushing inwardly or pulling outwardly upon the rod 37, the home plate can be spun in a desired direction.

The following rules and regulations are preferable in connection with the apparatus, 75 but the same rules that govern the National, American League and the American Association can be employed or special rules adopted before a game is started.

The game can be played by two persons, 80 each individual choosing a team, for instance a contest between Pittsburgh and New York. The names of the players or each team can be written in a score book or printed cards containing the lineup of the 85 various teams.

The game shall consist of nine innings and it is intended that the player representing the team "first up" shall play until three men on the side represented by the player 90 are out. Then the player releases the position to his opponent, who proceeds in the same way.

When a ball passes over the web of an opening, it is considered an "error". 95

When a ball rolls directly into and remains in any of the openings in the infield or in the outfield the batter is out, that is to say if the ball does not move out of the opening. If the ball should roll into and remain 100 in one of the openings in the foul field, the batter is also out. If the ball passes over the playing field and goes through any openings in the playing field, that is to say does not remain in any of the openings, the batter 105 is credited with a hit and takes first base.

If a ball should roll past the outfield openings, the batter is credited with a two-base hit and if it hits the outer walls 1 and 2 without going in the opening representing 110 home run, the batter is credited with a three-base hit.

It is to be understood generally that a ball on the rebound signifies nothing and that wherever it goes in its direct course represents value.

In any part of the field designated for strikes, it is intended that when a third strike is called it shall be out unless it should rebound by hitting the walls 3 and 4 and 120 enter the passed ball territory.

If a ball should roll directly into the stolen base territory, it is of course only to advance a player provided there is a player on base.

If a ball rolls into the foul territory, either to the right or to the left of the catcher and goes through one of the openings, it indicates that the catcher has caught the ball and the batter is out.

A third person shall act as an umpire and a fourth as an official scorer.

The base runner is indicated by the end of the lever 32 protruding upwardly through 5 one of the openings 9.

When a player upon a base is hit by a batted ball, the player is out.

When a batted ball goes to any one of the 10 outfield positions and rebounds, the batter is entitled to two bases and the player on the base is entitled to one base.

When a ball hits the opening of the pitcher and rebounds it is an error on the part of the pitcher and the batter goes to first base.

15 When a ball rebounds from first, second, third or shortstop openings, the batter is entitled to a base and the runner is entitled to a base if on the opposite side of the field from where the ball lands.

20 If the ball hits the openings of the margin of the outfield, the player is entitled to two bases, and when a ball hits the outer walls 1 and 2 in the fair territory and rebounds, it is a three base hit.

25 When a ball goes into the opening 7, it is a home run and the players are advanced accordingly.

A ball hitting an opening and rebounding represents an "error."

30 Adults familiar with the game of baseball will readily realize the merits of the apparatus for portraying the game, and as there is considerable uncertainty as to the delivery of the ball upon the apparatus, 35 considerable interest will be manifested, as the chances of winning or losing the game is an uncertainty and does not depend upon the skill or accuracy of a participant in the game.

40 The game apparatus in its entirety is made of light and durable material and as stated before of various sizes.

What I claim is:—

1. A game apparatus comprising a 45 rectangular frame, a field plate carried thereby and having edges cut away to provide openings, a return plate arranged in said frame below said field plate and inclined toward the rear end of said field plate, and 50 a revolute receptacle arranged upon said field plate and provided with spouts adapted to project a ball upon said field plate.

2. A game apparatus comprising a rectangular frame, a field plate arranged 55 within said frame and provided with openings, a revolute receptacle mounted upon said field plate and provided with spouts adapted to project a ball upon said field plate, and means arranged below said field 60 plate for conveying the projected ball to the rear end of said field plate.

3. A game apparatus comprising a rec-

tangular frame, a field plate arranged within said frame and provided with openings, a cup carried by the rear end of said field plate and in communication with the under side of said field plate, and a receptacle revolutely mounted upon said field plate and adapted to be spun to project a ball upon said field plate. 65

4. A game apparatus comprising a rectangular frame, a field plate arranged within said frame and provided with openings, a cup carried by the rear end of said field plate and in communication with the 75 under side of said field plate, a receptacle revolutely mounted upon said field plate and adapted to be spun to project a ball upon said field plate, and levers arranged below said field plate and adapted to project into 80 some of the openings thereof.

5. A game apparatus comprising a rectangular frame, a field plate arranged within said frame and provided with openings, an inclined return plate arranged in 85 said frame below said field plate, a cup carried by the rear end of said frame and in communication with the space between said field plate and said return plate, and means including a receptacle arranged upon said field plate for projecting a ball upon said field plate.

6. A game apparatus comprising a rectangular frame, a field plate arranged in said frame and provided with openings, 95 partitions arranged upon said field plate, a revolute receptacle arranged upon said field plate and provided with discharge spouts for discharging a ball upon said field plate, and means arranged in the same 100 plane as said field plate for partially closing some of the openings thereof.

7. A game apparatus comprising a rectangular frame, a field plate arranged in said frame and provided with openings, a 105 return plate arranged below said field plate and inclined toward the rear edge thereof, a cup carried by the rear edge of said field plate and in communication with the space between said field plate and said return 110 plate, a revolute receptacle arranged above said field plate and adapted to discharge a ball thereon, partitions arranged upon said field plate for guiding the movement of the ball discharged by said receptacle, and 115 means in the same plane as said field plate for partially closing some of the openings thereof.

In testimony whereof I affix my signature in the presence of two witnesses.
